UNITED STATES PATENT OFFICE

OSCAR SMITH, OF JUMP RIVER, WISCONSIN

BANKING PLOW FOR SNOW FENCING

Application filed April 28, 1928. Serial No. 273,615.

The object of this invention is to provide a plow with a lifting blade especially adapted to bank snow along a highway, at a reasonable distance therefrom, so that drifts toward 5 and into the highway will be checked or prevented.

A further object is to provide a plow in which the particular shape, position and mounting of the blade facilitate the work for 10 which the plow is intended.

With the foregoing and other objects in view, the invention consists in the novel construction and arrangement of elements described and claimed, it being understood that 15 modifications may be made within the scope of the claim, without departing from the spirit of the invention.

In the drawings,

Figure 1 shows the plow in top plan.

Figure 2 is in elevation, as seen from the right side.

Figure 3 is an elevation, looking from the rear.

Figure 4 is an elevation from the opposite 25 side, as compared with Figure 2.

Figure 5 is a bottom plan view.

Figure 6 is a section on line 6-6 of Figure 1.

Figure 7 is a section on line 7-7 of Figure 30 1.

Figure 8 is on line 8-8 of Figure 1.

A beam 10 is provided with a clevis 11, at the forward end, and has connected therewith transverse bars 12 and 13 secured to a 35 platform member or board 14 above which the seat 15 is mounted on supporting means 16.

A runner 18 is mounted parallel with the beam, and is connected therewith by a transverse bar 19, and a post 21 extends from the runner upwardly and is secured to transverse bar 19 and bar 12, said post being braced by diagonal bar or brace 22 connected at 23 with the beam 10. A forward transverse bar 24 is 45 connected with the beam, and with the curved plate member 26 disposed vertically, and constituting if desired a folded over portion of beam 10, assuming that portions 10 and 26 are of steel in bar or plate form.

50 A snow lifting blade 28 extends outwardly

and downwardly from element 26 (Figs. 2 and 8) and rearwardly thereof, the rear portion having considerable elevation as shown at 29, and an upper flange member 30 is secured to the blade by angle bar 31. The 55 tongue and re-entering angle type of joint shown in Figure 2, at the middle portion thereof, contributes to rigidity and good surface construction, at an important point in the machine or structure. The flange is 60 braced by the post 21 and by angle strip 32, and is held also by forward bracket 33. A relatively large angle bracket 34 extends under the blade and has secured thereto braces 35, 36. A forward brace on element 26, at 65 the upper edge, is designated 37, and a rear runner and guiding member is mounted at the rear end of beam 10, as shown at 38.

A better and more effective banking operation results from the use of this device, since 70 the snow can be piled to a greater height, and farther from the roadway.

Having described the invention what is claimed is:-

A snow banking plow, comprising a beam, 75 a plate element diverging outwardly and rearwardly from the forward end of the beam, a blade sloping downwardly in a transverse direction and upwardly and rearwardly in a longitudinal direction and connected 80 with the plate element, and an upwardly extending and rearwardly and outwardly curved flange having a surface at an angle with the blade and merging into the surface of the plate, the flange having connection 85 with said plate and blade, and the point where the plate meets the edges of the flange and blade presenting a tongue and reentering angle type of construction.

In testimony whereof I affix my signature. 90
OSCAR SMITH.
